UNITED STATES PATENT OFFICE.

JOSEPH DUFFY, OF PATERSON, NEW JERSEY.

ORGANZINE-SPINNER.

SPECIFICATION forming part of Letters Patent No. 631,563, dated August 22, 1899.

Application filed January 10, 1899. Serial No. 701,693. (No model.)

To all whom it may concern:

Be it known that I, JOSEPH DUFFY, a citizen of the United States, residing in Paterson, in the county of Passaic and State of New Jersey, have invented certain new and useful Improvements in Organzine-Spinners; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to machines for spinning organzine-warp; and it has reference particularly to that class of machine of this nature referred to, for example, in Letters Patent Nos. 525,192 and 602,254, issued to me August 28, 1894, and April 12, 1898, respectively.

The principal objects of the invention are to improve upon the mounting arrangement of the spindles for the delivery-bobbins of a machine of the class referred to and upon the stopping mechanism for the spindles of both the receiving and delivery bobbins.

In view of the foregoing the invention consists in the improved spinning-machine and in the combination and arrangement of its various parts, substantially as will be hereinafter described, and finally embodied in the clauses of the claim.

Referring to the accompanying drawings, Figure 1 is a sectional view of the machine provided with my improvements. Fig. 2 is a front view of a portion of my improved machine, enough of the mechanism being shown to clearly illustrate my invention; and Fig. 3 is a top plan view of that portion of the machine which is shown in Fig. 2, one of the spindles and its whirls being removed.

In said drawings, *a* indicates the usual spindle-rail of a spinning-machine, upon which are supported, as hereinafter described, the various spindles for both the receiving and the delivery bobbins.

a' indicates an auxiliary rail which is suspended beneath and parallel to the spindle-rail *a* by means of brackets *a'*.

b designates a series of cylindrical sockets which penetrate the spindle-rail *a*, each being sustained thereby through the medium of a rounded flange *b'* at its upper end, said

flange being slightly larger than the opening through which the socket projects. The diameter of the socket is slightly less than the opening through the spindle-rail, and the socket is therefore movable into various positions. The position of each socket is controlled by means of a bolt *b*, which projects through the auxiliary rail and through an elongated transverse aperture *b'*, formed in a flattened extension *b* at the lower end of said socket. The construction just described not only renders each socket adjustable, but also makes it possible to reverse the position of the same when the parts become worn unequally.

Each of the sockets receives and forms a bearing for the pintle *c* of the bolster *b* for the spindle of a delivery-bobbin, said bolster being carried by the pintle through the medium of a horizontal arm *c'*, integrally connecting these elements. The pintle has an enlargement *c*, which rests upon the top of the flange *b'* of the socket, and it is prevented from an undue upward movement out of the socket by means of a screw *c*, projecting through the wall of said socket and engaging an annular groove *c* in said pintle.

The bolsters for the spindles of the delivery-bobbins are arranged in pairs, and they project an appreciable distance beneath the spindle-rail, extending through elliptical or other elongated transversely-arranged openings *b* in said spindle-rail, so as to be free to move for some distance about the pintles as axes. The ends of a curved metallic spring bear against the downwardly-projecting ends of each pair of bolsters, said spring being rendered adjustable by means of a set-screw *d*, which works in a lug *d*, extending downwardly from the spindle-rail, said set-screw bearing against the spring midway its ends. Said spring is maintained against undue downward movement by flanges *d* upon the bolsters.

e e' designate the spindles for the delivery-bobbins, said spindles being journaled in the bolsters in any well-known manner and carrying the usual whirls *e* *e'*.

f designates the bolster for the spindle *f'* of the receiving-bobbin, said bolster being stationarily secured to the spindle-rail in any well-known manner. *f* designates the whirl

for said spindle f' , and g designates the continuous driving-belt which extends between the two series of whirls, being adapted to actuate said whirls so long as the spring d is free 5 to act to force the bolsters b^5 rearwardly.

h designates a rail or support from which projects forwardly a series of thread-guides h' , secured thereto in any desired manner and corresponding to the several delivery-bobbins.

10 i designates a rod connecting portions of the frame of the machine and over which the threads from the delivery-bobbins pass in their upward movement toward the arm j , which projects forwardly from a suitably-supported rail j' and over which said threads also extend.

k designates a thread-guide situated below the arm j and supported upon a suitable rail k' .

15 $l l'$ are two rollers disposed the one above the other, the lower one being journaled in a fixed position and the upper one being loosely journaled in recesses l^2 at the free end of a bifurcated lever m , fulcrumed upon a bracket m' , that is mounted upon a rail or beam m^2 of

20 the frame of the machine. Having passed the thread-guide k , the thread extends down back of the upper roller and then between the rollers, where the two threads from the delivery-bobbins are doubled, they having been previously twisted.

25 From the lower roller l' the thread extends downwardly to a spinning-ring n , of any well-known construction and carried upon a traverse-rail n' , controlled by a vertically-reciprocating rod or traveler n^2 , which is guided in a bracket n^3 , supported upon the spindle-rail a . The spinning-ring n incloses a receiving-bobbin n^4 , which is carried upon the spindle f' and upon which the thread or yarn is finally spun in the usual

30 manner.

o designates a hanging rod which is pivotally connected to the rear end of the lever m at its upper end and to which, near its lower end, is connected the braking devices for the several spindles.

35 The braking device consists of a curved or substantially horseshoe-shaped bar p , from each of whose free ends extends laterally an arm p' and from whose rear portion extends upwardly another arm p^2 , carrying a brake-shoe p^3 , preferably formed of rubber. The arms p' are adapted to bear against the bolsters of the spindles for the delivery-bobbins, and the brake-shoe p^3 of the arm p^2 is adapted 40 to bear against the whirl of the receiving-bobbin, and for this reason the curved bar straddles the bolster of the receiving-bobbin. It is obvious that the brake-shoe p^3 and the arms p' may be adapted to bear against any other 45 revolving portion of the driving means for the bobbins than those above particularly referred to, and consequently, moreover, the shape of the braking device proper may be somewhat altered, if desired. Said braking 50 device is operated through the medium of a bell-crank lever q , which is fulcrumed in a bracket q' , supported upon the spindle-rail a ,

one arm of said bell-crank lever being pivotally connected to the braking device and the other arm thereof being likewise connected to the 70 rod o . In order to permit a true vertical movement of said rod o , the arm of the bell-crank lever to which it is connected is provided with a slot q^2 , receiving the pivoting element. The weight of the rod o overbalances that of the roller l , and hence has a 75 tendency to lift said roller. The parts are normally sustained in the position in which they are shown in the drawings by an arm r , provided with a roller r' , which bears against the under side of the rear portion of the lever m , said arm being an upward extension of a weighted lever r^2 , which is fulcrumed in a projection r^3 of the bracket m' and whose rear portion normally bears against the under 85 side of said projection.

s designates a hanger pivotally secured to and depending from the rear end of the lever r^2 and carrying a block s' , which is supported upon slides s^2 of said hanger for horizontal 90 movement.

t designates one of a pair of fallers for the threads from the delivery-bobbins, and u designates a faller for the single thread which is produced after the doubling operation. 95 Each of these fallers is provided at its outer end with a loop t' and u' , respectively, through which the thread passes. The rear end of the faller t is connected to one arm of a bell-crank lever t^2 , which is fulcrumed in the 100 bracket m' and whose other arm is pivotally connected to the block s' . The rear of the faller u is pivotally connected to a lever u^2 , which is fulcrumed in a bracket u^3 , extending from the rail m^2 , and is so curved and weighted at its free end as to tend to draw the faller 105 rearwardly. The faller u is guided for horizontal movement by a bracket u^4 , extending from the rail m^2 . A connecting-rod u^5 is pivotally secured to the lever u^2 and the block 110 s' , being adapted to transmit movement from the former to the latter.

v designates a spur-wheel which is situated in contiguity to the block s' , being constantly rotated while the machine is in operation. 115

It should be remarked that, if desired, a guide w , supported upon the rail m^2 , may be provided for steadyng the lower end of the hanger s .

y designates a rod which extends above and 120 substantially parallel to the spindle-rail a , being supported thereon by suitable standards y' . This rod is inclosed in a tube y^2 , preferably formed of rubber and somewhat loosely secured theron, so as to be turned 125 into various positions. It will be noticed that the rod y is disposed directly opposite to the whirls of the spindles of the delivery-bobbins and that it forms an abutment against which they may impinge.

130 The operation of the machine may be thus described: The several whirls are normally maintained in operative contact with the driving-belt g by means of the spring d , which

tends to force the whirls $e^2 e^3$, carried upon the bolsters b^5 , rearwardly about the pintles c as axes. It will be seen that if the thread breaks at any point between the rollers $l l'$ and the delivery-spindles the weight of the faller t will be free to actuate the bell-crank lever t^2 and the block s' , which latter element will consequently be moved so as to be engaged by the spur-wheel v , the impact of which wheel forces the hanger downwardly, and consequently turns the lever r^2 upon its fulcrum, so that the arm r , which normally supports the lever m , will permit the latter, owing to the weight of the rod o , to fall. If the thread breaks between the roller l' and the receiving-bobbin, the weighted lever u^2 will act to move the block s' into engagement with the revolving spur-wheel v , with the same ultimate dropping of the rod o as a result. This dropping of the rod o will throw forward the braking device proper, the brake-shoe p^3 bearing against the whirl and stopping the rotation of the spindle f' and the arms $p p'$, forcing the bolsters b^5 forwardly against the action of the spring d and into such position that the whirls $e^2 e^3$ will bear against the rubber tube on the rod y and their rotation stopped. The separation of the two sets of whirls will of course effect a release of the belt g , so that it will no longer act upon them.

It should be remarked that when the lever m is actuated the rollers $l l'$ are immediately separated and their action on the thread stopped.

Having thus fully described my invention, what I claim as new, and desire to secure by Letters Patent, is—

1. The combination, with a spindle-rail, of a bolster-support depending therefrom, and means, connecting the lower end of said support with the spindle-rail, for effecting a lateral or substantially horizontal adjustment of the former, substantially as described.

2. The combination, with a spindle-rail, of a cylindrical socket or sleeve penetrating said rail and provided with a sustaining-flange at or near its upper end, a pintle journaled in said sleeve, a bolster carried by said pintle, and means, connecting the lower end of said sleeve with the spindle-rail, for effecting a lateral or substantially horizontal adjustment of the former, substantially as described.

3. The combination, with a spindle-rail, of a cylindrical socket or sleeve penetrating said rail and provided with a rounded sustaining-flange at or near its upper end, a pintle journaled in said sleeve, a bolster carried by said pintle, an auxiliary rail arranged beneath said spindle-rail and means for adjustably connecting the lower end of said sleeve with said auxiliary rail, substantially as described.

4. The combination, with a spindle-rail, of cylindrical sockets or sleeves penetrating said rail and provided with rounded sustaining-flanges at or near their upper ends, pintles journaled in said sleeves, bolsters eccentric-

ally carried by said pintles, an auxiliary rail suspended from said spindle-rail, and means for adjustably connecting the lower ends of said sleeves to said auxiliary rail, substantially as described.

5. The combination, with a spindle-rail and with driving means, of bolsters mounted in said rail, spindles revolubly mounted in said bolsters and having operative engagement with said driving means, and means, controlled by the thread or yarn, for disengaging some of said spindles from their driving means and braking the others, substantially as described.

6. The combination, with a spindle-rail and with driving means, of bolsters mounted in said rail, spindles revolubly mounted in said bolsters and having operative engagement with said driving means, an abutment mounted on said rail and means, controlled by the thread or yarn, for moving some of said spindles out of engagement with their driving means and into engagement with the abutment and for braking the others, substantially as described.

7. The combination, with a spindle-rail and with a driving-belt arranged above the same, of bolsters mounted in said rail, spindles revolubly mounted in said bolsters on each side of, and having operative engagement with, said belt, and a device, controlled by the thread or yarn, for disengaging some of said spindles from the belt and for braking the others, substantially as described.

8. The combination, with a spindle-rail and with a driving-belt arranged above the same, of bolsters mounted in said rail, spindles revolubly mounted in said bolsters on each side of, and having operative engagement with, said belt, an abutment mounted on said rail, and a device, controlled by the thread or yarn, for moving some of said spindles out of engagement with the belt and into contact with the abutment and for braking the others, substantially as described.

9. The combination, with a spindle-rail and with a driving-belt arranged above the same, of spring-actuated and movable pairs of bolsters mounted on said rail on one side of said belt, stationary bolsters mounted on said rail on the other side of said belt, spindles revolubly mounted in said bolsters and operatively engaging said belt, an abutment mounted on said rail contiguous to the spindles on the movable bolsters, and devices, controlled by the thread or yarn, for moving the movable bolsters and their spindles from the belt to the abutment and for braking the stationary spindles, substantially as described.

10. The combination, with a spindle-rail and with a driving-belt arranged above the same, of spring-actuated and movable pairs of bolsters mounted on said rail on one side of said belt, stationary bolsters mounted on said rail on the other side of said belt, spindles revolubly mounted in said bolsters and operatively engaging said belt, an abutment mounted on said rail contiguous to the spindles on

the movable bolsters, and stopping devices for the spindles each consisting of a curved rod controlled by the thread or yarn and provided with arms on their extremities, adapted to engage a pair of the movable bolsters, and with a brake-shoe adapted to engage a spindle on a stationary bolster, substantially as described.

In testimony that I claim the foregoing I have hereunto set my hand this 22d day of 10 December, 1898.

JOSEPH DUFFY.
